UNITED STATES PATENT OFFICE.

FRANK R. DOANE, OF VANDALIA, MICHIGAN.

STOVE OR FURNACE ATTACHMENT.

Application filed December 2, 1922. Serial No. 604,528.

To all whom it may concern:

Be it known that I, FRANK R. DOANE, a citizen of the United States, residing at Vandalia, in the county of Cass and State of Michigan, have invented a new and useful Stove or Furnace Attachment, of which the following is a specification.

This invention relates to heating stoves, furnaces, or the like, and has for its object 10 the provision of a device in which the products of combustion are divested of approximately all heat units before being permitted to escape to the chimney flue.

Another object of the invention is the provision of a device in which the relatively cool 15 air, at the bottom of the furnace is transferred to the center of the heating unit where it is subjected to a more intense heat before delivery to the apartment to be 20 heated.

Other objects will present themselves as the description proceeds, it being within the province of the disclosure to improve generally, devices of that class to which the 25 present invention appertains. It will, of course be understood that slight changes may be made within the scope of what is claimed without departing from the spirit 30 of the invention or sacrificing any of the advantages thereof.

In the drawing:-

Figure 1 is a vertical transverse sectional view of a heating plant constructed in accordance with the present invention, there 35 being parts shown in elevation.

Figure 2 is a bottom plan view of a portion of the structure.

Figures 3 and 4 are plan views of baffle plates used in connection with the invention.

Figure 5 is a sectional fragmental plan view taken on line 5-5 of Figure 1.

Figure 6 is a central vertical sectional view of a modified form of heater.

Figure 7 is a central vertical sectional view of a still further modified form of heater.

Referring to the drawings by characters of reference the letter A designates a heater which may be considered as representative 50 of any form of heater, steam, hot water, or hot air. The fuel burning compartment comprises a casing 1 having an upper end wall and is provided with the usual stoke door 2 and ash door 3.

A casing 4 spaced from the heater 1 to 55 form a compartment 5 is supported on a frame 6, having an opening 7 from the compartment 5 for the circulation of cold air. An outer casing 8 extending from the floor line to the ceiling and spaced from the casing 4 provides a second compartment 9, which communicates with the room above through an opening 10, the first mentioned compartment also communicating with the room through an opening 11. 60

A drum 12 having a closed top and provided with openings 13 in its bottom, is located in the combustion chamber of the heater, directly over the fuel compartment. 70 Pipes 14 connect the drum with the atmosphere, outside the furnace through openings 15 formed in the front of the heater.

A tubular member or flue 16 which may be termed a super-heater, has an upper open end 17, the bottom being closed by the drum 12 on which it rests. A plurality of pipes 18 are connected to the member 16 near the bottom thereof, the said pipes extending into the compartment 5, are there provided with downturned ends 19 which reach to a point 80 near the opening 7, admitting cold air to the super-heater.

Baffle plates 20 and 21 are supported in spaced relation within the combustion chamber and surrounding the super-heater 16. 85 The plates having notches or cut away portions 20^a and 21^a respectively, the notches being formed on one plate near the center and on the other at the periphery thereof, the plates being placed alternately to effect a tortuous passage for the products of combustion flowing to the outlet 22 at the top of the heater.

A pipe 23 leads from the opening 22 to an auxiliary heater designated generally by the letter B. A heat chamber 24 is provided with a clean out door 25 and a casing 26 spaced from the member 24 provides a hot air compartment 27. Surrounding the casing 26 and spaced therefrom is a second casing 28 forming an outer or cold air compartment 29, the compartments 27 and 29 registering with the room above through openings 30 and 31 respectively. 95

A frame 32 supports the casing 26 above the bottom of the furnace forming an opening 33 for the passage of air from one to the other of the compartments 29 and 27. 100 105

Connected to the pipe 23 at a point within the compartment 27 is a pipe 34 which extends downwardly to a point near the bottom of the heat chamber 24, where it enters the said chamber and is here provided with an upturned end 35. The end 35 of the pipe 34 opens directly beneath the closed end of a secondary super-heater 36 which is located centrally of the heat chamber 24 and extends to the top thereof. Baffle plates 37 and 38 similar to the plates 20 and 21 respectively and similarly arranged, provide a tortuous passage for the products of combustion through the heat chamber to an opening 39 near the top of said chamber. A pipe 40 leads from the opening 39 to the smoke stack or chimney.

Pipes 41 are connected to the super-heater near the bottom thereof, and are directed 20 downwardly in the chamber 27, as indicated at 42, being similar to the pipes 18 and for the same purpose.

In operation with combustion taking place in the fire box of the heater 1, the said products pass through the baffle plates 20 and 21, heat radiating from the side walls of the heater 1 into the compartment 5 to rise through the opening 11 into the room above. The cold air of the room flows through the 25 opening 10 and compartments 9 to the bottom of said compartment where it rises in the space 5 to be heated in its passage therethrough. A portion of the cool air enters the pipes 18, is conducted to the member 16 30 to be heated and passes through the open end 35 to 17 the opening 11.

The products of combustion are conveyed through the pipe 23 to the heater B, where practically the same action takes place as heretofore described in connection with the heater A. The residue of combustion being discharged from the pipe 35 rises in the member 24 and is discharged through the stack. Circulation of air being downwardly 45 from the room above through the opening 31, compartment 29 then upwardly through the compartment 27 and opening 30 back to the room, a portion passing through the member 36.

50 As shown in Figure 5 the pipes 14 leading from the drum 21 to the exterior of the furnace are connected to a header 43 which is in communication with the openings 15, the flow of air into said openings being governed by a damper plate 44, it being in this way possible to admit a limited amount of air to the top of the fuel to promote combustion of the gases formed in the combustion chamber above the fuel.

60 In Figure 6 a slightly modified form of stove is shown comprising an outer casing 45 and an inner casing 46 spaced apart to form a compartment 47. Short flues 48 connect the compartment 47 with the outer air, near the floor so that a circulation of air is

established through said compartment, the heated air escaping at the top of the casing.

A member 48 corresponding with the member 16 heretofore described is located in the combustion chamber 49 over the fire pot, the member 48' is provided with a pipe 50 which opens to the outside of the casing 45 and establishes a circulation of air through said pipe and member 48', the heated air passing out through the perforated top 51. Products of combustion pass from the chamber 49 through baffle plates 52 and 53, to heat the air in the member 48, and escape to the chimney through the opening 54.

Figure 7 depicts a heater 60 in which is located a super-heater 61. A flange 62 formed about the upper open end of the member 61 provides a closure for the top of the stove and also serves to support the superheater in the combustion chamber.

Baffle plates 63 and 64 are supported within the heater and prevents rapid flow of heated air therefrom to the smoke flue.

The member 61 being detachable from the heater may be used in many forms of stoves 90 now on the market or in use.

It will be evident that a furnace built as herein described will provide a heating plant in which practically all heat will be removed from the products of combustion, thereby effecting quite a saving in fuel consumption.

Having thus described the invention, what is claimed is:—

1. In a device of the class described, a heater comprising a furnace; a casing spaced from the furnace to form an air heating compartment; a second casing spaced from the first mentioned casing to form a cold air compartment, the two compartments being in communication for the circulation of air therethrough; a secondary heater comprising a heat chamber, a casing surrounding the heat chamber and spaced therefrom to form an air heating compartment; a second casing surrounding the other casing and spaced therefrom to form a cold air compartment, the two compartments communicating for the circulation of air therethrough and means for connecting the furnace with the heat chamber.

2. A furnace comprising a combustion chamber having an upper end wall, a tubular member extending downwardly into the combustion chamber from said end wall, a casing spaced from the combustion chamber to form a heating compartment, a second casing spaced from the first mentioned casing to form a cold air compartment, the two compartments communicating for the circulation of air therethrough, and a pipe connecting the bottom of the tubular member with the said air circulating compartments.

3. A furnace comprising a combustion chamber having a closed upper end wall, a tubular member extending downwardly into

the combustion chamber from said end wall, the tubular member being closed at its lower end, baffles in the casing about the tubular member, means for admitting air to the lower end of the flue from a point external to the combustion chamber, a drum beneath the tubular member, the drum having air outlets discharging into the combustion chamber, conduits connected to the drum and having an air inlet external to the com-

bustion chamber and a damper for controlling the said air inlet to the conduits.

In testimony that I claim the foregoing as my own, I have hereto affixed my signature in the presence of two witnesses.

FRANK R. DOANE.
